UNITED STATES PATENT OFFICE.

KNUTE EDAHL, OF CHICAGO, ILLINOIS, ASSIGNOR TO CAMEL COMPANY, OF CHICAGO, ILLINOIS, A CORPORATION OF ILLINOIS.

CAR-DOOR STRUCTURE.

Application filed July 7, 1927. Serial No. 203,859.

The present invention relates to car door structure.

More particularly the present invention relates to the side doors of railway house cars and has for one of its objects the provision of means for taking the weight of a sliding door off the bearings of said door when said door is in a predetermined position, as for instance, the fully closed position of said door.

A further object is to provide a car door structure of the kind immediately above referred to, which has the advantage that the free sliding of the door is not interfered with except when the door is at or approaching the predetermined position referred to.

A further object is to provide a structure for taking the weight of a freight car door off its bearings, which structure is combined with the door guides.

Further objects will appear as the description proceeds.

Referring to the drawings—

Figure 1 is a fragmentary view of the main and supplementary door of an automobile car, which doors have applied thereto embodiments of the present invention;

Figure 2 is a sectional view taken along the plane indicated by the arrows 2—2 of Figure 1;

Figure 3 is a sectional view taken along the plane indicated by the arrows 3—3 of Figure 1;

Figures 4 and 5 are views on an enlarged scale of parts of the structure shown in Figure 1;

Figure 6 is a vertical sectional view illustrating a top hung door embodying the principles of the present invention; and

Figures 7 and 8 are fragmentary views taken on an enlarged scale illustrating embodiments of the present invention applied to the top of the door shown in Figure 6.

Though Figures 1 and 2 show the main and supplementary doors of an automobile car, it will be clear that the invention is not limited to this type of car, but applies to other sliding doors as well.

The numeral 10 indicates the main door and the numeral 11 indicates the auxiliary or supplementary door of a car, the supplementary door being provided with the movable door jamb 12. As shown in Figure 1, the doors 10 and 11 are bottom supported, which is to say that said doors have a bearing

upon a track at the bottom of said doors, said bearing being had by means of roller bearings indicated by the numerals 13—13, said roller bearings being located adjacent to the front and rear edges of said doors.

The track for supporting the roller bearings 13—13 is indicated by the numeral 14. Said bearings 13 are disposed within brackets 15, which may be riveted or otherwise secured to the material of the door upon which they are mounted. Any preferred means, which need not be described herein, may be utilized to maintain the door in its proper plane in a direction transversely of the car.

According to the present invention, means are provided for lifting the doors off the roller bearings 13 when the doors are in predetermined positions, which are the closed positions of said doors in the illustrated embodiments of the invention. To accomplish this purpose, each door adjacent to its forward and rear edges is provided with a bracket 16 having a downwardly presented cam surface 17. Mounted upon the framework of the car in position to be engaged by the brackets 16—16 are the brackets 18, each of which has the upwardly presented cam surface 19. The brackets 16 and 18 are so disposed that the cam surfaces thereof engage when the corresponding door is in home or closed position. By reason of the cam shapes of the mutually engaging surfaces of the brackets 16 and 18, the doors will be lifted as they approach home position, whereby the weight of the door will be removed from the bearings.

The brackets 16 and 18 should be so disposed that when the bracket 16 on the front edge of the door moves to a position above the bracket 18 at the rear edge of the doorway, said brackets should not engage with one another. For this purpose the bracket 18 at the front edge of the doorway should have the uppermost part of its cam surface at a higher level than the uppermost part of the cam surface of the bracket 18 at the rear of the doorway. Expressed in other language, the elevations of the top portions of the cam surfaces of the brackets 18—18 at the front and rear edges of the doorway should be sufficient to cause cooperative relationship between the bracket 16 at the front edge of the door and the bracket 18 at the front edge of the doorway and the bracket 16 at the rear edge of the

door and bracket 18 at the rear edge of said doorway, and to preclude operative relationship between the bracket 16 at the front edge of the door and the bracket 18 at the rear edge 5 of the doorway.

Referring now to Figures 6, 7 and 8, a top hung door is illustrated the bottom of which is held against movement transversely of the car by the guides 20—20 which are secured 10 to the body of the car. Said brackets are mounted adjacent to the front and rear edges of the doorway controlled by said door. Each of said brackets is provided with an upwardly presented cam surface 21 adapted to cooperate 15 with the cam surface 17 of each corresponding bracket 16 mounted upon the door. The uppermost parts of the cam surfaces 21—21 of the two brackets 20 at the front and rear edges of the doorway should be at different 20 levels, the uppermost portion of the cam surface 21 of the bracket at the front edge of the door being at a higher level than the uppermost portion of the cam surface 21 of the bracket at the rear edge of the doorway. The 25 reason for this difference in levels will be clear from the discussion above in connection with Figures 1 to 5.

It will be clear that once the brackets 16—16 on the door have been freed from the corresponding brackets upon the body of the car, the door may roll upon its bearings without interference between said brackets. Only when the door is moved to home position do the brackets upon the door engage with the 35 brackets upon the car body. Any preferred door opening and closing means may be utilized to move the door when the brackets referred to are in cooperative relationship with one another.

Though certain preferred embodiments of the present invention have been described in detail, many modifications will occur to those skilled in the art. It is intended to cover all such modifications as fall within the scope of 45 the appended claims.

What is claimed is—

1. In combination, a car body, a sliding door therefor, bearings for said door, brackets upon said door adjacent to the front and 50 rear edges of said door, and brackets upon said car body adjacent to the front and rear edges of the doorway controlled by said door, the brackets upon said door being adapted to engage the brackets upon said car body to lift said door from its bearings when said door 55 is in a predetermined position, the uppermost level of the cooperating surfaces of said

brackets at the front edge of said doorway being higher than the uppermost level of the cooperating surfaces of said brackets at the 60 rear edge of said doorway.

2. In combination, a car body, a top hung sliding door for said car body, brackets carried by said car body for guiding the lower edge of said door, and brackets upon said door adapted to have cooperative relationship with said first mentioned brackets for lifting said door from its bearings when said door is in a predetermined position, the brackets upon said car body being disposed 65 adjacent to the front and rear edges of the doorway controlled by said door, the uppermost part of the cooperating engaging surfaces of said brackets being higher at the 70 front edge of said doorway than at the rear 75 edge thereof.

3. In combination, relatively stationary means providing a doorway, a sliding door therefor, bearings for said door, cam means upon said relatively stationary means, said cam means being located adjacent to the front and rear edges of said doorway, cam means upon said door adjacent to the front and rear edges of said door, the cam means upon said door being adapted to engage the cam means 80 upon said relatively stationary means to lift said door from said bearings when said door is in a predetermined position, the uppermost level of the cam surface of the cam means carried by said relatively stationary means at 90 the front edge of said doorway being at a higher level than the uppermost level of the cam surface of the cam means carried by said relatively stationary means at the rear edge 95 of said doorway.

4. In combination, relatively stationary means providing a doorway, a top hung sliding door for said doorway, cam means carried by said relatively stationary means adjacent to the front and rear edges of said doorway, cam means carried by said door adjacent to the front and rear edges of said door, said cam means upon said door being adapted to have cooperative relationship with said cam means upon said relatively stationary means 105 for lifting said door from its bearings when said door is in a predetermined position, the uppermost parts of the cooperating engaging surfaces of said cam means being higher at the front edge of said doorway than at the 110 rear edge thereof.

Signed at Chicago, Illinois, this 1st day of July, 1927.

KNUTE EDAHL.
